UNITED STATES PATENT OFFICE

WILLIAM TIMSON, OF SOHO FOUNDRY, BIRMINGHAM, ENGLAND, ASSIGNOR TO W. & T. AVERY LIMITED, OF BIRMINGHAM, ENGLAND

DESIGN FOR A SCALE HOUSING

Application filed July 5, 1932, Serial No. 44,256, and in Great Britain April 16, 1932. Term of patent 7 years.

To all whom it may concern:

Be it known that WILLIAM TIMSON, residing at Soho Foundry, Birmingham, England, a subject of the King of Great Britain, has invented a new, original, and ornamental Design for a Scale Housing, of which the following is a specification, reference being had to the accompanying drawing, forming part thereof.

Figure 1 is a front perspective view of the

scale housing showing my new design. Figure 2 is a rear perspective view thereof.

The dominant feature of my design resides in the upper part of the scale housing above the line $a-a$.

I claim:

The ornamental design for a scale housing, as shown and described.

WILLIAM TIMSON.
